Ser. No. 76,780

Term of patent 14 years

(Cl. D57—1)

FIG. 1.

FIG. 2.

FIG. 3.

FIGURE 1 is a front perspective view of a face mask for a helmet showing my new design, the broken line showing of the helmet being for illustrative purposes only;

FIGURE 2 is a front elevational view thereof; and

FIGURE 3 is a sectional view taken on line 3—3 of FIGURE 2.

The present application is a division of my earlier filed copending patent application entitled "Face Mask For A Helmet," Serial No. D. 72,825, filed December 12, 1962.

The characteristic feature of my design for the face mask for a helmet disclosed resides in the pattern of ornamentation applied to the front thereof, as shown.

I claim:

The ornamental design for a face mask for a helmet as shown and described.
